Primary Examiner — Cynthia Underwood(74) *Attorney, Agent, or Firm* — Douglas W. Sprinkle**CLAIM**

The ornamental design for a nut and seal, as shown and described.

DESCRIPTION

FIG. 1 is a front elevational view illustrating a preferred embodiment of the nut and seal of the present invention, said front elevational view being identical to a rear elevational view;

FIG. 2 is a front bottom elevational view thereof;

FIG. 3 is a top plan view thereof;

FIG. 4 is a front view of the design which is identical to the rear view thereof; and,

FIG. 5 is a bottom plan view thereof.
